END LABEL ATTACHMENT

Phil G. Schlemmer, Nanuet, N. Y., assignor to
American Machine & Foundry Company, a cor-
poration of New Jersey

Application April 2, 1938, Serial No. 199,577

15 Claims. (Cl. 216—29)

This invention relates to a mechanism for applying patch-like parts to packages, especially to the end-folds of wrappers enveloping articles of the nature of loaves of bread, and more particularly relates to improvements in such a mechanism adapted to be included in or combined with the general organization of such a wrapping machine as that disclosed in and forming the subject matter of the co-pending application, Serial No. 171,388, filed by Schmidt and Jackson, 10 wherein individual labels are fed from a stack and applied to the ends of the wrapped packages, said application having been assigned to the owner of the present application.

In pursuance of the above general object, it is 15 a more particular object to provide coordinated instrumentalities by which a continuous supply of labeling material in strip form is fed under a brake-and-spring control from a supply roll thereof, and from which supply strip individual labels are severed and transferred successively to the ends of the wrapped packages respectively.

Another object is to provide means by which to prevent slippage of the supply strip and thus to assure proper registration of the conventional or other printed matter with which each label may be provided, by the formation of the printed label-supply strip with marginal indentations occupying a definite position intermediate the spaced-apart prints, and arranged to be engaged with correspondingly spaced, raised circumferential feeding elements of a feed wheel.

This feed wheel, in further pursuance of the invention, is designed to cooperate with a pair of co-acting feed-rolls to advance a desired length of the strip to a severing station where a severing device is provided, adapted to operate intermittently at predetermined intervals, and provision is also made of a clamping device arranged to be engaged with the strip at suitable intervals 40 in order to hold the same for each severing operation.

A further novel provision of the invention in this connection, includes means by which a clamp finger is adapted to engage the label and is biased normally toward such engagement for holding the label from shifting as the severing means operates, and is released as the severing device moves to fulfill its duty of severing the label from the strip, so that the bias is made effective and each label is properly held for the severing operation.

A further object of the invention is to provide for co-ordinating the above-described mechanisms with a mechanism for transferring each 55

severed label to its appropriate end of the wrapped package, and for applying the label to said end, preferably corresponding in essential details with the mechanism for that purpose disclosed in said application, Serial No. 171,388.

Other objects and features of the invention will appear as the description of the particular physical embodiment of the invention selected for illustration progresses.

In the accompanying drawings, like characters of reference have been applied to corresponding parts throughout the several views which make up the drawings, in which:

Fig. 1 is a side view of label feed mechanism in the construction of which the present invention has been embodied;

Fig. 2 is a fragmentary view in side elevation of the label feed mechanism, illustrating the driving and clamping means for feeding the label supply strip;

Fig. 3 is a view in sectional plan of the parts shown in Figs. 1 and 2, the view being taken on the line 3—3 of Fig. 1, the knife and some other elements associated therewith having been omitted from Fig. 3; Fig. 4 is a partial detail view in plan taken on the line 4—4 of Fig. 1 and serving to illustrate the knife actuating means more clearly; portions of various parts associated with the knives being also shown;

Fig. 5 is an end view taken from the view point defined by the line 5—5 of Fig. 1, and showing the label guide and clamp finger;

Fig. 6 is a diagrammatic plan view showing the label gripper wheel applying the label to one end of the package;

Fig. 7 illustrates the form of label used in conjunction with the unit; and

Fig. 8 is a perspective view showing the label affixed to one end of the package.

In referring to the drawings, it should be understood that a labeling unit of the type herein disclosed is provided at each side of the article-way of the wrapping machine, the position of which is indicated at A in Fig. 6, and along which move suitable pusher devices, of known or other suitable form, as indicated by a part of a pusher, designated 183 in Fig. 6, serving as means for advancing the loaves P in the direction of travel indicated by the arrow. Each labeling unit will be adjacent to an end of each of the packages successively, in the same manner as shown in Fig. 1 of the previously mentioned patent application. It will be also understood that the labeling units are mounted on adjustable bars to permit in-and-out adjustment to accommodate pack-

ages of different lengths, and that the main driving means of the units are identical with that shown in the heretofore mentioned application for patent.

A driven bevel gear 10, Fig. 3, attached to one end of a shaft 11, Figs. 1 and 2, imparts motion to a sprocket 12 driving a chain 13 running over a sprocket 14 fastened to one end of a shaft 15. Shaft 15 is provided with a feed roller 16, which, with co-acting knurled portions K, K', upon the adjacent peripheries of the roll parts 32, 33, engages, and takes up any slack in, the label supply strip W as it advances from the wheel 35. The shaft 15 is provided with a gear 19, meshing with a gear 20, mounted on the shaft 18, and thereby imparting motion to the roller 17.

The shafts 11 and 15 are supported by side frames 21 and 22 which may be suitably attached to a wrapping machine, as indicated generally by the reference character C. The shaft 18 is carried by arms 23 and 24 fulcrumed on studs 25 and 26, respectively, supported in extending arms 27 of said side frames. Arms 23 and 24 are connected by a tie bar 28, and the arm 23 is provided with a post 29 supporting one end of a tension spring 30 supported at its other end by a post 31 carried by the side frame 21, said spring being provided to hold the gears 19 and 20 in mesh.

The hub of feed roller 17 may have the part 33 formed integrally therewith, and contiguous with the part 33 is a separately formed ring-like part 32, fitted on the shaft 15, as shown in Fig. 3, the part 32 being provided with an arcuate slot permitting adjustment of the part 32 rotatively with respect to the roller parts 33-17. In this manner the raised knurled or feeding portion K' of the roll 32 may be adjusted with respect to the knurled portion K of the roll 33, thereby to lengthen or to shorten the region of engagement with the label strip W, and thus to regulate the amount of the strip taken up or fed. When the desired relationship of the roll part 32 with the roll parts 33-17 is obtained, it is fixed in place by the set-screw 34.

The strip registering wheel 35 is provided at its circumference with spaced, raised inserts 36 which are of suitable shape to conform with the shape of indentations 37 formed in the margins of the label strip W, Fig. 7. The wheel 35 is mounted on a shaft 38 supported at one end in a bracket 39 secured to the side frame 21, and its other end is supported in a bracket 40 fastened to the side frame 22. A gear 41, fixed on the shaft 38, is driven by a gear 42 (Fig. 2) mounted on a stud 43 supported in bracket 40. Stud 43 also supports a sprocket 44 driven by means of a chain 45 running over sprocket 46 mounted on the drive shaft 11.

A cam 50 (Figs. 2 and 3) attached to shaft 11, actuates a cam roller 51 carried by an arm 52 which at its other end is clamped on to a pivot shaft 53 supported by the bracket 40. An arm 54 clamped to the other end of shaft 53 supports a rod 55 carrying a clamp plate 56. Cam 50 is set in such relation to the feed roller 17-32 that as the feeding portion of said roller leaves the strip W the clamp plate 56 will descend onto the strip and hold it from displacement during the cutting operation, which will be hereinafter described. A tension spring 57 is provided, tending to hold the cam roller 51 in engagement with cam 50.

The supply roll of labeling material R, Fig. 1, is carried by a reel 60 loosely mounted on a shaft 75

61 supported by bracket 39. The strip W as it is unwound from the reel R is led over a roller 62 and over wheel 35, and in passing over the latter care must be taken that the indented portions 37 of the strip W (Fig. 7) shall register with the raised members 36 of wheel 35, and the strip is then passed under clamp 56 and between the feed rollers 16 and 17. Stripper fingers 63, extending from a holder 64, and attached to bracket 39 (Figs. 1 and 3) engage in the grooves 65 of wheel 35 and tend to direct the strip under the clamp plate 56, and they also prevent the strip from clinging to the wheel 35.

As the strip is advanced by the feed rollers, it is directed downward by curved portions 66 and 67 of a guide plate 68 and a ledger plate 69, respectively. Plate 68 is attached to an extending arm 70 of a bracket 71 (Figs. 1 and 5) and the ledger plate 69 is carried by the side frames 21 and 22, Figs. 1 and 4. The leading end of the strip enters into the gap between guide plate 72 and a backing plate 73, Fig. 1, the strip in this position being ready for severance by a knife 74 (Figs. 1 and 4).

When the high portion of the rollers 17-32 is about to leave the strip W, the clamp plate 56 descends onto the section of strip overlying the table 75, stopping its advance and holding it from displacement during the cutting operation. The knife 74, in moving to sever a label from the strip releases a clamp finger 76, permitting the same to engage and hold the label portion of the strip during the cutting operation. The strip and label portion being thus clamped by the clamp plate 56 and clamp finger 76, which countervail both the feeding and any tensional effect, the knife completes its duty of severing a label from the strip, the label being severed across the indentations as illustrated by dot and dash lines in Fig. 7. The knife now retreats and in approaching its original position moves the finger 76 from its clamping position, allowing the severed label to drop against an adjustable plate 77 (Figs. 1 and 5) which provides means for centering the label L vertically on the package P as shown in Fig. 8. Plate 77 may be moved up and down to suit different label sizes by manipulation of an adjusting screw 78 of the type shown in the heretofore mentioned patent application.

The label is withdrawn from its compartment by a revolving gripper wheel 80 (Fig. 6) provided with cam actuated gripper fingers 81 which nip one end of the label L, shown in dotted lines, and carry it past a revolving drum 82 which applies a coating of adhesive to the label, which is backed by the circular portion 83 of wheel 80. As the gripper wheel is preferably of the identical construction disclosed in the previously mentioned patent application, a more detailed showing and description is deemed unnecessary, in the interest of brevity.

Meanwhile, the feed wheel 35 has continued feeding the strip W, thereby forming a loop between the clamp plate and the wheel. At the time the clamp plate 56 is lifted from the strip, the leading high portion 33 of rollers 17-32 engages the strip and with the aid of roller 16 advances the slack portion of the strip. Inasmuch as the rollers travel faster than wheel 35, the adjustable rollers 17-32 are set in respect to the member 35 so that as the strip is pulled taut, the raised portion of the roll is about to leave the strip, at which instant the plate 56 descends upon the strip and clamps the forward section thereof. The plate 56 thus acts to

countervail any tension exerted upon the severed end of the strip at the time of severance, and holds it ready for the next feeding movement by the high portion 33 of rollers 17—32.

The package P (Fig. 6) in being propelled through the runway of the machine, has its extending wrapper ends folded by suitable folder plates 84 situated at each end of the package. When the leading end of the label L is applied to the end of the package, the gripper fingers 81 are opened, and the remaining portion of the label is rolled onto the end of the package, the continued advancement of the package bringing it into contact with suitable heated members as at 184, which fuse the folded wrapper ends about the package. By heating the wrapper the adhesive applied to the label L is caused to penetrate the softened wax coating of the wrapper and adhere to the underlying paper. The finished package P has the appearance shown in Fig. 8.

The knife 74 is actuated by the cam surface 85, which is provided at the end of roller 16 (Fig. 4) and the latter engages a cam roller 86 carried by a stud 87 (Fig. 2) fastened to an extending arm 88 of the knife. A spring 89 spanned between a stud 81, and a spring post 90, Fig. 4, tends normally to hold the knife 74 in the position seen in Fig. 4. The knife is held in engagement with its ledger 69 by a compression spring 91 lodged in a block 92, secured to frame 22.

The clamp finger 76 (Figs. 1, 4 and 5) is guided in a hub 95 of bracket 71 and at its upper end carries a fixed arm 96 engaging the edge of knife 74. A spring 97 is provided to hold said members in engagement. As the knife moves to perform its cutting action, the spring 97 swings arm 96, permitting the end of finger 76 to engage the label.

In pursuance of a stated object of the invention, a let-off mechanism for the strip is provided which includes a braking arrangement to overcome overrunning of the strip W when unwound from roll R, Fig. 1. The arm 100 which carries the guide roller 62 is fulcrumed on a stud 101 supported on an arm 102 of bracket 39, and one end of the bar 103 connects to a brake strap 104 which partly surrounds the hub 105 of reel 60. The other end of strap 104 is looped around a stud 106 carried by an arm 107 of bracket 39. When the strip W is being fed, it has the tendency to move arm 100 toward wheel 35, whereby the strap 104 will become loose about the hub 105 and allow the reel 60 to turn freely, but if the reel should deliver too much material, the arm 100 will move away from wheel 35 and gently tighten the strap 104 about the hub 105 and retard the turning of reel 60. The movement of arm 100 is controlled by a tension spring 108 fastened at one end to stud 106 and having its other end attached to a screw 109 at the upper end of arm 100. Screw 109 provides means for adjusting the tension of spring 108, and consequently the braking action of members 104—105.

A receptacle as at 182, in which the adhesive is stored, has a bearing supporting a vertical shaft 110 (Fig. 6) which carries the adhesive drum 82, and the shaft 110 is provided at its lower end with a bevel gear 111 in mesh with a bevel gear 112 mounted on a horizontal cross shaft 113. Shaft 113 is continuously driven by suitable means from a motor (not shown) of the machine, and therefore drum 82 will continue to rotate even when the main clutch of the machine is disengaged, stopping the machine for the purpose of replenishing the wrapped material or to

make necessary adjustments to accommodate different sizes of packages.

In the previously mentioned patent application, the drum which supplies the adhesive to the label is driven by means connected to the main clutch, and therefore when the clutch is disengaged said drum will stop and the adhesive on the portion of the drum not in contact with the adhesive in the receptacle, will become hard or tacky, necessitating cleaning of the drum after practically every stoppage of the machine. By the present arrangements this hindrance is overcome, resulting in an increase of production.

Between each folder plate 84 and the heater 184 on the same side of the articleway, where the gripper wheel 80 is arranged to apply the adhesive-coated label to the end of the loaf as already described, provision is preferably made of a stripper member having stripper fingers 99 which pass behind the label L as it is carried around on the periphery 83 of the gripper wheel 80. The wheel preferably is grooved circumferentially to receive the ends of the stripper fingers 99 as indicated by a dotted line. The fingers 99 are preferably heated to facilitate the stripping action, and for this purpose a heater 98 is provided.

What is claimed is:

1. Mechanism for affixing labels to the ends of each of a series of wrapped loaves of bread; said mechanism comprising an articleway; means to advance said wrapped loaves along the articleway in side by side disposition with the loaf ends exposed for attachment thereto of said labels; a support for a supply-roll of label strip material having opposed semi-circular marginal indentations of the same size; a strip-feed device including opposed peripheral feeding elements for entering said indentations at each edge of said strip and for feeding the same at a predetermined linear speed to a severing station; a label-applying station in a path intersecting said articleway; means at said severing station to sever said strip at intervals substantially at the midpoint of each indentation, to form labels therefrom; means to feed said labels from said severing means past said label-applying station; and means to attach a label in adhesive contact against each end of said articles individually as they pass said label-applying station.
2. The combination with means for continuously advancing wrapped loaves at constant speed, of means for severing label parts from a stock strip, mechanism for rendering said label-forming parts adhesive, mechanism for rolling said label parts against the ends of the advancing packages with their adhesive coated faces in contact therewith, and heaters arranged to engage the labeled package ends.
3. A label applying mechanism comprising a support for a supply roll of label-strip, means to sever labels therefrom serially, mechanism to advance articles to a label-applying station, means to deliver each label to a compartment, means to grip each label in turn and transfer it from said compartment to the article to be labelled, at said label-applying station, and means to cause adherence of said labels respectively, each to the end of an article to be labelled, by the application thereto of a rolling pressure with heat.
4. A label applying mechanism comprising a device for parting labels successively from a supply strip of label material and moving the labels serially edgewise in one direction into an up-

right position, mechanism to present a package at a labeling station, means for gripping an upright edge of a label and moving the label edge-wise in another direction to carry said edge into engagement with the end of a package at said station, means to render said label adhesive in the course of said transfer, and means to cause said label to adhere smoothly and completely against said package end.

5. In a labeling mechanism, means for advancing wrapped loaves past a label applying station, devices for applying labels at said station to the ends of an advancing series of said wrapped loaves, said devices including heaters arranged to engage and heat-seal the labels to the ends of the packages, and members for holding the labels on the package ends until they contact said heaters, means for supporting a supply strip of label stock, means to part labels from said strip, means to advance said labels individually into the range of action of said label-applying devices and means for simultaneously adjusting said devices, heaters and strip-feed and severing means to accommodate loaves of various lengths with said labels properly centered.

6. In a labeling mechanism comprising a label-strip-feed, means to sever labels therefrom, and means to tension the leading end of said strip preliminary to severance, mechanism including a pocket means to hold the severed end of said strip against said tension, and a means to hold each label part in upright position subject to transfer to a labeling station, said pocket means being constructed and arranged to permit introduction of the severed label edgewise thereto in an upright plane and its removal edgewise therefrom in said upright plane in another direction.

7. In a labeling mechanism comprising a label-strip-feed, means to tension said strip, means to sever the tensioned strip into labels, and means to countervail said tension and feeding at severance, substantially as described.

8. A labeling attachment of the class described, comprising a support for a strip-supply roll, a let-off mechanism on said support, including means for tensioning the strip and a primary feed roll also on said support and having feeding elements adapted to engage the margins of said strip to draw it off positively against said tension and to advance the strip positively, a compartment on said support to receive the leading end of the strip when so advanced, means to sever the strip at a region intermediate said feed roll and compartment, leaving the severed end as a label in said compartment, and clamping devices adapted respectively to hold the label forming end, and to hold the strip part anterior to the region of severance, during the severing operation.

9. A strip feeding and severing mechanism for labeling machines and the like, said mechanism comprising a primary feed roll having feeding elements adapted to be engaged with marginal indentations of a supply strip to control the advancement thereof, a severing device, a secondary feed roll couple, the rolls of which are carried by parallel shafts, with intermeshing gears, one of said shafts and its roll and gear being supported floatingly, and said last-named roll having a radial enlargement adapted to be revolved intermittently into engagement with the leading portion of said strip to advance a predetermined label-size length of said end to said severing means.

10. In a labeling mechanism, the combination with a pocket having upright front and back portions arranged to provide a label receiving space which is relatively shallow from front to rear to hold the label in an upright plane, said pocket being open at its upper edge and along one side edge to permit the introduction of labels into the pocket from above and the removal of labels in said pocket from the side for application to an article, a support for a supply of labels in continuous strip form, means to feed labels from said supply into said pocket, and mechanism for severing said labels from said strip.

11. The mechanism set forth in claim 10 where-in said label feeding means is arranged to deliver the label at the forward end of the continuous strip into said pocket, said severing mechanism being timed relative to said feed to sever the label after delivery of the same into said pocket.

12. In a labeling mechanism, the combination with an article way along which articles to be labeled are forwarded, of a label receiving chamber adjacent said way having separate label receiving and delivering openings, means providing a source of supply of printed labels in continuous strip form, a label cutter, mechanism cooperating with said cutter for feeding said strip transversely of the direction of movement of the articles along said way, past said cutter through said receiving opening and into said chamber to provide a succession of cut labels in said chamber, and label applying means operating to remove each cut label edgewise through said delivery opening in a direction at an angle to that in which the label was delivered to the chamber and to apply the same to an article forwarded along said way.

13. The mechanism set forth in claim 12 having devices cooperating with said chamber to vary the position of the labels in said chamber so as to adjust the position of the label when applied to said articles.

14. Mechanism for affixing labels to loaves provided with wrappers having a thermoplastic constituent; said mechanism including a support for a continuous strip of label-supply material; means for advancing said loaves with their thermoplastic wrappers to a label-applying station; means for feeding severed adhesive label parts to said label-applying station; means for advancing successive portions of said strip to a severing station; means at said severing station to sever label-forming parts from said strip; means for rendering said label parts adhesive; a pocket means to receive each label, as severed from said severing means; means to withdraw a label from said pocket and to feed it to the path transversed by a wrapped loaf end; and means to heat seal said adhesive label-strip parts to said thermoplastic wrapper parts.

15. The combination with devices for parting coated labels from a continuous supply strip, means to advance packages to a label-applying station, means to advance said labels from said parting devices to said station, and means for applying said labels at said station to the aligned ends of an advancing series of packages, of heaters arranged to engage and heat seal the labels to the ends of the packages, said applying means including members for holding the labels on the package ends until they contact said heaters.

PHIL G. SCHLEMMER.
